UNITED STATES PATENT OFFICE.

WILLIAM F. SELLERS, OF EDGEMOOR, DELAWARE, ASSIGNOR TO EDGE MOOR IRON COMPANY, OF EDGEMOOR, DELAWARE, A CORPORATION OF DELAWARE.

BOILER CONSTRUCTION.

1,148,544.

Specification of Letters Patent.

Patented Aug. 3, 1915.

Application filed November 25, 1914. Serial No. 873,851.

To all whom it may concern:

Be it known that I, WILLIAM F. SELLERS, a citizen of the United States, residing in Edgemoor, Brandywine Hundred, county 5 of New Castle, and State of Delaware, have invented a certain new and useful Improvement in Boiler Construction, of which the following is a true and exact description, reference being had to the accompanying 10 drawings, which form a part thereof.

The general object of my present invention is to improve the construction of the headers of steam generating boilers and like structures in which a chamber wall subjected to internal pressure, is formed with hand hole openings spaced comparatively closely together and has stay bolts attached to it between the hand holes.

More specifically one object of my invention is to shape the wall containing the hand holes so as to strengthen the latter, and so as to directly utilize the strength and rigidity of hand hole covers having tapered or conical portions entering the hand hole 25 openings from their inner ends and plugging said openings strengthening the wall containing the hand hole openings.

Other specific objects of my invention are to provide a wall construction shaped to effect the first mentioned specific object of my invention with seats adapted to receive and accurately position the external dogs by which the hand hole covers are secured in place, and which will permit the hand hole 35 cover seats to be readily and inexpensively formed in a very accurate manner.

In carrying out my invention I forge or die press the plate or wall containing the hand hole openings to form internal flanges 40 surrounding the hand hole openings and providing the seats for the conical plug portions of the hand hole covers. These flanges are merged into the flat portion of the wall to which the stay bolts are attached so that 45 the portions of each pair of flanges at opposite sides of any stay bolt, form in effect the sides of a more or less flat arch to the crown of which the stay bolt is attached.

The various features of novelty which 50 characterize my invention are pointed out with particularity in the claims annexed to and forming a part of this specification.

For a better understanding of my invention however, and the advantages possessed 55 by it, reference should be had to the ac-

companying drawings and descriptive matter in which I have illustrated and described a preferred construction embodying my invention.

Of the drawings: Figure 1 is a front elevation of a portion of a water tube boiler in which my invention is employed. Fig. 2 is a partial section on the line 2-2 of Fig. 1. Fig. 3 is a partial horizontal section on the line 3-3 of Fig. 1. Fig. 4 is a partial vertical section on the line 4-4 of Fig. 1. Fig. 5 is a partial inclined section on the line 5-5 of Fig. 1.

In the drawings, A represents the front header of water tube boiler and B represents the water tubes thereof.

C is the steam and water drum of the boiler.

The header A is formed with substantially parallel front and back walls *a* and *aa* respectively. The water tubes B which pass through apertures formed in the rear wall *aa* are expanded to rigidly secure them in the latter. The front header wall *a* is formed with round hand holes *A*¹ one in line with each water tube B. The wall or plate *a* is forged or die pressed to provide a flange portion *A*² at the margin of each hand hole opening as is shown clearly in Fig. 3. Each flange portion appears as a reverse curve in cross section radial to the hand hole opening, the curve merging at its inner end into one of the flattened portions of the wall *a* in which plate the hand hole openings proper are formed, and merging at its outer end into the outer flat portion of the plate *a* to which are attached the outer ends of the stay bolts D employed to connect the walls *a* and *aa*. Preferably as shown, each hand hole opening *A*¹ is slightly flared at its inner end. Each hand hole opening is closed by means of a hand hole cover F comprising a conical portion *F*¹ which, with the surrounding flexible bushing E of copper or the like, projects into the inner end of and fills the hand hole opening. The base of the hand hole cover is larger in diameter than the hand hole opening except at opposed sides *F*², *F*³, where it is flattened to permit of the edgewise passage of the hand hole cover through the hand hole opening.

The hand hole cover construction disclosed is that covered by the Sellers & Bradford patent 1,105,212, granted July 28, 1914.

Each hand hole cover is formed on its

outer side with a threaded socket to receive the one end of the bolt G by which the cover is secured to the external dome shaped dog H. The forging or die pressing of the 5 plate to form the flange portions A² is advantageously so carried out to provide a recessed seat A³ at the margin of the outer end of each hand hole opening for the corresponding dog H. Advantageously also, 10 each hand hole cover is formed with a finger F² adapted to engage an adjacent stay bolt to prevent a rotation of the hand hole cover when a wrench is applied to a nut at the outer end of the bolt G to remove or 15 tighten up the hand hole cover.

In the formation of a header such as the one illustrated in the drawings, the plate forming the wall a is preferably punched and flanged, and the tube and hand hole 20 openings are bored or reamed usually in the same setting of the boring or reaming machine and before the plate is riveted into the header. After the walls of the header are riveted together, the inner end of each 25 hand hole opening is advantageously finished to the shape requisite for the hand hole cover. This treatment of the hand hole seats as the final steps in the manufacture 30 of the header avoids all possibility of distortion of the seats due to strains in the metal set up during the construction of the header.

The construction described is simple and effective and insures an accurate formation 35 of the seat for each hand hole cover F, and the accurate seating of the dog H by which the hand hole cover is secured in place. The flanges A¹ and A² directly contribute to the strength of the wall a required to resist the tendency to rupture or distort the 40 plate at the margin of each hand hole opening and the point of attachment to each stay bolt and indirectly strengthens the plate by its reaction against the portions of 45 the hand hole covers which plug the hand hole openings.

By referring to Figs. 3 and 4 of the drawings it will be apparent that each hand hole cover serves as the key-stone or crown portion of a dome, the remainder of which is 50

formed by the surrounding flange portion A². Reference to these figures also shows that the adjacent portions of each pair of flanges a¹ at opposite sides of each stay bolt form the sides of an arch to the flattened 55 crown of which the stay bolt is attached. The spreading apart of the sides of this arch is directly opposed, of course, by the corresponding hand hole covers F. The flatness of the arches depends on the spacing 60 of the hand holes, and with the spacing shown the arches shown in vertical section are flatter than those shown in horizontal section as is clearly shown by Figs. 3 and 4.

Having now described my invention, what 65 I claim as new and desire to secure by Letters Patent is:

1. A boiler header comprising an opposing pair of walls one of which is formed with a plurality of hand hole openings and 70 with internal flanges surrounding said openings, and in combination therewith stay bolts connecting said walls and secured to the wall in which the hand holes are formed between the latter, and hand hole covers 75 comprising tapered plug portions which enter and jam in said hand hole openings from the interior of the header.

2. A boiler header comprising an opposing pair of walls one of which is formed with a plurality of hand hole openings and 80 with internal flanges surrounding said openings and with an external recessed seat surrounding each hand hole, and in combination therewith stay bolts connecting said 85 walls and secured to the wall in which the hand holes are formed between the latter, hand hole covers comprising tapered plug portions which enter and jam in said hand 90 hole openings from the interior of the header, and hand hole cover securing means comprising an external clamping dog or follower connected to each cover and shaped to engage and be centered by the corresponding seat.

WM. F. SELLERS.
